SPEEDBOAT

Piotr F. Lapidovsky, Wilmington, Del.

Application December 12, 1940, Serial No. 369,885

11 Claims. (Cl. 115—63)

This invention is a high-speed boat, particularly for military purposes.

The most important factor in retarding the progress of a boat through the water is the friction between the hull of the boat and the water. If this friction can be greatly reduced, the speed of the boat can be correspondingly increased.

The principal object of this invention is to reduce the friction between the hull of the boat and the water. When a boat goes through the water at, say, twenty miles an hour, friction is set up between the water, which is stationary, and the hull, which is moving twenty miles an hour. If, however, the hull is provided with a movable sheath or envelope which is driven rearwardly by power, at the same speed that the boat is moving forwardly, this sheath or envelope is, with respect to the water, stationary, and therefore the skin friction between the water and the hull is greatly reduced by reason of the use of such a power driven movable sheath or envelope.

In the preferred embodiment of the invention, the boat comprises a pair of very long pontoons which are braced apart in parallel and longitudinally extending relationship so as to form a double hulled boat. These pontoons form the supporting and water-displacing portion of the boat. They are water-tight and are of sufficient size so that the interior of the pontoons can be used for fuel oil or gasoline, ammunition, cargo space, etc.

The two pontoons are strongly braced apart throughout their extent by a rigid framework or deck which may serve to carry the necessary engine or engines and the necessary ordnance, such as a 75 mm. gun, machine guns, anti-aircraft guns, torpedo tubes, etc.

Each of the described pontoons is provided with at least one, and preferably three, endless belts. Such a belt provides a movable sheath or envelope, which confines between it and the hull a thin layer of water which moves along with the pontoon or hull, thereby reducing friction between the hull and the water. One of these belts lies underneath the bottom of the pontoon and is of about the same width as the bottom of the pontoon; this belt passes around the ends of the pontoon and from bow to stern thereof on the top of the pontoon. Each pontoon at each end is provided with a hollow drum which has four pairs of belt-engaging teeth. The pontoons are also provided with intermediate sprocket wheels placed between the two drums, proportionally carrying an equal length of the belt.

Each side of each pontoon, to a height a little above the water line, is provided with a vertically extending belt which is connected to the described bottom portion of the belt, the three portions of the belt therefore surrounding as much of the pontoon as is in the water.

The three belt sections described above are driven as a unit so that the bottom stretch of the belt, that part in the water, with respect to the boat, moves rearwardly as fast as the boat moves forwardly, so that it is in effect stationary with respect to the water. The top stretch of the belt would therefore move, with respect to the water, at twice the speed of the boat.

15 The described friction reducing belts may assume several forms. In the preferred embodiment of the invention these belts are formed by wires, of about the strength and size of piano wires, braced in parallel and abutting relationship and being so held by being gripped at suitable intervals between gripping plates, about every ten feet. Built into the belt of piano wires are a number of main cables, preferably four, and these cables receive the driving power from the 20 driving drums and transmit such power to the wires through the gripping plates or clamps above mentioned.

25 The boat is propelled preferably by an internal combustion engine power plant driving an air propeller. However, a water propeller could be used instead of the air propeller, or both types of propulsion could be used.

30 Power for driving the friction reducing belts is preferably obtained from a power plant for each belt; however a common power plant for the two belts could be used. A separate power plant is preferably provided for propelling the boat.

35 The pontoons provide a large storage space for fuel oil, so that the boat has a very large cruising range, without the necessity of refueling. This is very important from the military point of view. The high speed of the boat is also evidently of great importance, enabling it to attack 40 quickly, to escape from more heavily gunned vessels, and to avoid aircraft bombs.

45 Referring now to the accompanying drawings, illustrating the present preferred embodiment of the invention:

50 Fig. 1 is a side elevation of the fore part of the boat;

Fig. 2 is a plan view thereof;

Fig. 3 is a side elevation of the aft part of the boat;

55 Fig. 4 is a plan view thereof;

Fig. 5 is an enlarged bottom plan view of a portion of one of the pontoons;

Fig. 6 is a side elevation of the aft end of one of the pontoons, on an enlarged scale;

Fig. 7 is a section on the line 7—7 of Fig. 5;

Fig. 8 is a sectional view of a detail; and

Fig. 9 is a view of a modification.

Referring now to these drawings, in which similar reference characters indicate similar parts, the boat comprises a pair of pontoons 2 extending the entire length of the boat. These pontoons are substantially rectangular in cross section and have vertical side walls 4. These pontoons are of sufficient size so that when the entire boat is in the water the water line is about one-third of the way up the side walls of the pontoons. When in motion, the boat would draw about three feet.

The two pontoons are braced apart in rigid parallel relationship by a strong rigid frame or truss indicated generally by 6. The truss 6 supports any necessary decking as may be desired and as many fore and aft torpedo tubes 8 as may be desired. The deck may also be provided with a 75 mm. gun, anti-aircraft guns and the like.

The boat is preferably driven by an air propeller 10, the engine for which is in the housing or fuselage 12. A Pratt & Whitney engine of about 1850 H. P. may be used. The forward end of the fuselage may be provided with a 75 mm. gun, 14.

Each pontoon is provided with an endless belt indicated generally at 16. This belt is preferably formed of a plurality of closely spaced abutting parallel wires 16, of the caliber and strength of piano wires. Such a belt, in which the wires 16 are in abutting, side-by-side relationship, as shown in Fig. 8, forms an insulating sheath or envelope, confining between it and the hull a thin layer of water which travels along with the hull, acting as an insulating layer for reducing frictional drag between the hull and the water. Yet there is no frictional drag between such sheath or envelope, and the water below it, because it is substantially stationary with respect to such water below it. These wires, every few feet, are clamped between bars or clamping plates 18, which in turn are clamped together by bolts 20.

The clamping plates 18 are angularly positioned as shown in Fig. 5, and near the apex point are welded as at 22, to a cross bar 24.

The belt 16 also comprises, as an important part thereof, a plurality of relatively large cables 26, preferably four in number, and the cross bars are welded as at 27 to the inner pair of these cables 26, and welded to the head of center bolt 20.

The cables 26 are also gripped between the wire gripping plates 18, 18, one of such plates being provided with substantially U-shaped recesses 28 for this purpose.

The wires 16, cables 26, the gripping plates 18 and the cross bars 24, together constitute a unitary assembly forming the bottom and top stretches of the endless belt.

At or near the apex of the angle formed by the plates 18, there is mounted a water-proof ball bearing wheel 29, which rolls along and bears against the outside of the bottom wall of the pontoon 2, and against the outside of the top wall of the pontoon.

The endless belt of wires 16 is driven by intermediate sprocket wheels 30, and by cylindrical

drums at the bow and stern ends of the pontoons. Sprockets 30 are mounted in wells 31 in the pontoons 2. Sprockets 30 are provided with teeth 32 which engage with the cross bars 24, near the ends thereof, the belt of wires 16 being provided with suitable apertures 32a for accommodating the teeth 32. The ends of the wires, adjacent the apertures 32a, are anchored in any suitable way to the ends of bars 24 and to the plates 18.

The belt of wires 16, at the bow and stern, pass around cylindrical drums 33, the ends of the pontoons being curved as at 2a to accommodate these drums and being provided with arcuate passageways 2b, a little wider than teeth 32, for accommodating such teeth. These drums are provided with two sets of belt-engaging or sprocket teeth 32, there being four teeth in each set. These teeth 32 engage bars 24 in the same way as teeth 32 on wheels 30. In order to accommodate the plates 18 and bars 24 as they pass around the drums 33, these drums are provided on their surfaces with flattened areas 33a, which extend longitudinally, that is, parallel to the axis of the drum. The wires 16, cables 26, and ball bearings 29, pass smoothly around the exterior of the drums 33.

The sprockets 30 and drums 33 are mounted on transverse driving shafts 34, and these shafts are provided with gears 36 meshing with gears 38 mounted on longitudinal driving shafts 40.

The driving shafts 40 are in turn driven by driving chains 42, engaging with sprocket wheels on the shafts, these chains in turn being driven by sprockets from an engine 46 carried by the truss-work 6 between the pontoons. The engine 46 may be an engine of the Liberty motor type of about 400 H. P.

Instead of one engine 46 as just described, there may be provided two engines 47, as in Fig. 9, above each drive shaft 40, these engines driving gears 48, which mesh with gears on shafts 40 for driving the shafts.

The vertical or side portions of the endless belt are indicated generally at 50. Each side portion is also composed of wires, such as piano wires, gripped and clamped by and between the vertically extending plates 18' which may be regarded as an extension of the clamping plates 18. At the upper ends thereof, the plates 18' are provided with stub shafts 52, on the ends of which are mounted ball bearing wheels 54 which engage in and roll along in longitudinally extending channeled guideways 56, secured on the outside of the vertical walls 4 of the pontoon 2. Plates 18 on the bottom and 18' on the side are secured together as a unitary assembly, the guideway 56 providing the necessary support for preventing sagging of the lower stretch of the belt. Guideways 56 are widened and curved, as at 57, where they are adjacent the ends of drum 33.

In order to compensate for the variation in effective length of the wires as they go around the drums 33 at the fore and aft ends of the pontoon, these side wires 50, as shown in Fig. 6, are arranged in groups. The ends of all the wires of one group are secured to the plates 18'. The other ends of the wires of this group are clamped between pairs of plates 58, the lower ends of each pair of such plates being pivoted as at 60, while tension springs 62 are provided to pull the plates 58 toward the adjacent bars 18'. As the wires 50 travel around the drums 33, the inner wires would tend to become slack, and this

is prevented by the tension springs 62 which compensate for this variation and keep the wires taut even while they go around the drums. After the wires get around the drums the plates 58 assume their original position, as shown at the upper part of Fig. 6. Instead of springs 62 connected to plates 58, it is apparent that individual smaller springs could be attached to the end of each wire, for accomplishing the same purpose.

The clamping plates 18, cross bars 24, etc., although in the water, offer no frictional resistance to the boat, because the lower stretches of the endless belts are practically stationary with respect to the water.

The belt is so driven that its lower stretch is driven rearwardly at substantially the same speed the boat moves forwardly. However, if more power is applied to the belts, it is evident that they would have a propelling effect, while if slowed down, or reversed, it would have a powerful braking effect, particularly in reverse. Suitable gears and transmission could be provided, as desired, for controlling the speed and direction of travel of the belts. The propelling effect of the belt could be increased as desired by providing transverse paddles or the like, for accentuating the gripping or traction effect on the water.

There has thus been provided a high speed boat, capable of travel for long periods because of the large storage space for fuel in the pontoons; the boat is wide and low, providing stability and low visibility. It may carry a formidable armament of light artillery and torpedo tubes.

While the preferred embodiments of the invention have been described in some detail, it should be understood that the invention is not limited to these details, but may be carried out in other ways.

I claim as my invention:

1. A speed boat, comprising an elongated water-displacing hull, providing a trackway for an endless belt, an endless belt extending completely around said hull and operable on said trackway, the upper and lower stretches of said belt being located above and below the water line, respectively, said belt being composed essentially of a plurality of wires in closely spaced, side by side relation, said wires serving to confine between them and the hull, a relatively thin insulating layer of water for reducing the drag between the hull and the water and power means for driving said endless belt.

2. A speed boat, comprising an elongated water-displacing hull, blunt-nosed at bow and stern, and providing a trackway for an endless belt, an endless belt extending completely around said hull and operable on said trackway, the upper and lower stretches of said belt being located above and below the water line, respectively, said belt being composed essentially of a plurality of wires in closely spaced, side by side relation, said wires serving to confine between them and the hull, a relatively thin insulating layer of water for reducing the drag between the hull and the water and power means for driving said endless belt.

3. A speed boat, comprising an elongated water-displacing hull, providing a trackway for an endless belt, an endless belt extending completely around said hull and operable on said trackway, the upper and lower stretches of said belt being located above and below the water line, respectively, said belt being composed essentially of a plurality of wires in closely spaced, side by side relation, said wires serving to confine be-

tween them and the hull, a relatively thin insulating layer of water for reducing the drag between the hull and the water, power means for driving said endless belt and power means for driving a screw propeller, for driving said boat.

4. A speed boat, comprising an elongated water-displacing hull, blunt-nosed at bow and stern, and providing a trackway for an endless belt, an endless belt extending completely around said hull and operable on said trackway, the upper and lower stretches of said belt being located above and below the water line, respectively, said belt being composed essentially of a plurality of wires in closely spaced, side by side relation, said wires serving to confine between them and the hull, a relatively thin insulating layer of water for reducing the drag between the hull and the water, power means for driving said endless belt and power means for driving a screw propeller, for driving said boat.

5. A speed boat, comprising an elongated hull providing a trackway for an endless belt, an endless belt extending longitudinally over and around said hull, said belt comprising a main portion traveling in a horizontal plane and side portions traveling in respective vertical planes, sprocketed drums and wheels carried by the hull, in operative engagement with the belt, and power means for driving said drums and sprocket wheels.

6. A boat of the character described, comprising a cargo carrying, water displacing hull, a friction-reducing, relatively thin, endless belt, forming a sheath or envelope extending around said hull in a fore and aft direction, above and below the hull, the upper and lower stretches of the belt being located above and below the water line, respectively, and power means for driving said belt.

7. A boat of the character described, comprising a cargo carrying, water displacing hull, a friction-reducing, relatively thin endless belt, forming a sheath or envelope extending around said hull in a fore and aft direction, above and below the hull, the upper and lower stretches of said belt being located above and below the water line, respectively, said belt serving to confine between it and the hull, an insulating layer of water, power means for driving said belt, and propeller means for driving the boat.

8. A boat of the character described, comprising a cargo carrying, water displacing hull, a friction-reducing, relatively thin endless belt, forming a sheath or envelope extending around said hull in a fore and aft direction, above and below the hull, the upper and lower stretches of said belt being located above and below the water line, respectively, said belt consisting essentially of a plurality of wires, in parallel, side-by-side, abutting relationship, and serving to confine between the wires and the hull an insulating layer of water, and power means for driving said belt.

9. A boat of the character described, comprising a cargo carrying, water displacing hull, a friction reducing, relatively thin and substantially flat endless belt comprising bottom and side portions, forming a sheath or envelope below the bottom and along both sides of the hull, said belt being substantially continuous and serving to confine between it and the hull, an insulating and friction reducing layer of water, and power means for driving said belt.

10. A boat of the character described, comprising a pair of elongated, water-displacing, cargo-carrying pontoons, framing means for

holding said pontoons in spaced, parallel relationship, a relatively thin, friction-reducing endless belt extending around each of said pontoons, above and below the same, the upper and lower stretches of each belt being respectively above and below the water line of its pontoon, and power means for driving said belts.

11. A boat of the character described, comprising a pair of elongated, water-displacing, cargo-carrying pontoons, framing means for holding said pontoons in spaced, parallel relationship, a relatively thin, friction-reducing end-

less belt extending around each of said pontoons, above and below the same, the upper and lower stretches of each belt being respectively above and below the water line of its pontoon, said belt consisting essentially of a plurality of wires in parallel, side-by-side, abutting relationship, which serve to confine between them and the hull, an insulating layer of water, power means for driving said belts and propeller means for driving the boat.

PIOTR F. LAPIDOVSKY.
